(57) **CLAIM**

An ornamental design for a vehicle front bumper cover outer panel, as shown and described.

DESCRIPTION

FIG. 1 is a left side elevational view of a left vehicle front bumper cover outer panel (the right vehicle front bumper cover outer panel being a mirror image and is not shown);

FIG. 2 is a right side elevational view of the vehicle front bumper cover outer panel;

FIG. 3 is a front elevational view of the vehicle front bumper cover outer panel;

FIG. 4 is a top plan view of the vehicle front bumper cover outer panel;

FIG. 5 is a bottom plan view of the vehicle front bumper cover outer panel; and,

FIG. 6 is a perspective view of the vehicle front bumper cover outer panel.

The broken lines and surface members enclosed in the broken lines shown in the faded lighter tones are for illustrative purpose only and form no part of the claimed design.
